UNITED STATES PATENT OFFICE.

GEORGE DUBOIS, OF CHICAGO, ILLINOIS.

COLLAPSIBLE BOAT.

1,117,350.

Specification of Letters Patent. Patented Nov. 17, 1914.

Application filed September 20, 1913. Serial No. 790,825.

To all whom it may concern:

Be it known that I, GEORGE DUBOIS, a subject of the Emperor of Germany, residing at Chicago, in the county of Cook and State 5 of Illinois, have invented certain new and useful Improvements in Collapsible Boats, of which the following is a specification.

The essential object of this invention is to provide a boat having a collapsible framework of a type which permits setting up 10 very quickly, and which, when once set up, will remain in set-up position as rigidly to all intents and purposes as if the same were permanently fastened together.

15 In the drawings, Figure 1 is a top plan view of the framework; Fig. 2 is a side elevation thereof; Fig. 3 is a section on the line 3—3, Fig. 2, showing the framework in set-up position; Fig. 4 is a view similar to Fig. 3, showing the framework when collapsed; Fig. 5 is a detail of one of the devices for keeping the framework set up; and Fig. 6 is a view of the construction at the bottom of each rib.

20 25 An oval frame 1, which is shaped according to the shape which it is desired to give to the top of the boat, is provided with upwardly-extending ears or lugs 2, which ears 2 are perforated so as to permit reception 30 of the bolts 3. The number of ears 2 may be varied according to circumstances, but in the drawings the boat is depicted as having one at the stern, one at the bow, and two upon each side of the boat.

35 40 The bottom 4 may be made out of any suitable material and of any desired shape, though same must conform to the shape of the frame 1. In the drawings, the bottom 4 is depicted as being a sheet metal plate slightly curved so as not to provide a perfectly flat bottom. When the flanged edge 5 of the bottom 4 is secured by bolts 6 to the bottom or bent bar 7 which extends completely around the boat serving as a reinforcement and protection, the bolts 6 are secured in place by nuts 8.

45 Extending transversely of the boat are the I-beams 9 which are secured in any desired manner either to the bottom 4 or to the bar 7. Said beams 9 are provided at each end with teeth 10. At the bow of the boat and secured to the bottom is an I-beam 11 toothed at 12, and at the stern is an I-beam 14 toothed at 15. Although the members 9, 11, and 14 are herein described as being I-beams, that particular form of beam

is employed only as a matter of convenience and any other device for providing teeth 10, 12, and 15 will suffice.

The bifurcated lugs 16 are pivoted to the 60 respective ears 2 by the bolts 3, and depending from each bifurcated lug 16 is a rib 17, which ribs are depicted in the drawings as being T-beams. As best shown in Figs. 5 and 6, said ribs 17 are slotted at their lower 65 ends, and on each side of each slot 18 are provided with a projecting finger 19, which fingers 19 reach beneath the under edge of the top rail of the I-beam 9, and thus the projecting fingers 19 keep the ribs 17 at all 70 times secured to the I-beams. Those ribs 17 which are at the bow and stern are constructed similarly to the side ribs which 75 co-operate with the cross-beams 9, and are secured to the beams 11 and 14 in the same manner as the side ribs are secured to the cross-beams 9.

Assuming that the boat is in collapsed condition, the parts will assume the positions respectively indicated for them in Fig. 8c 4, and the side ribs 17 will have their lower or inner ends in the position depicted in said Fig. 4. If the person who desires to use the boat thereupon grasps the oval frame 1 and lifts same upwardly while the bottom 4 85 still remains upon the ground or in the water and carries the oval frame 1 from the position of Fig. 4 to that of Figs. 2 or 3, the respective ribs 17 will ride upon the beams 9, 11, or 14 which the ribs respectively engage, and the tooth 20 which is at the bottom of the main body portion of each rib 17 and which is above the slot 18 will seat in the corresponding ratchet 10, 12, or 15, and thus the frame 1 will be locked in elevated 95 position and the boat set up. To permit collapsing the boat it is necessary to release the teeth 20 from the ratchets which they respectively engage, thus permitting the lower ends of the ribs 17 to slide inwardly 100 upon the I-beams and toward the center of the boat; but merely to lift the oval frame 1 upwardly will cause the ribs 17 to ride along the I-beams until the ribs 17 are locked by the teeth or ribs at the outer edges 105 of said beams. Links 21 may be pivoted to the ribs 17, each of which links 21 has a hook-like end 22 adapted to be received within a perforation 23 in the I-beam, which links, therefore, serve to lock the framework in set-up position and prevent an unexpected or premature collapse of the boat 110.

because of accidental disengagement of the teeth 20 and the ratchets which said teeth engage.

The bottom 4 will, of course, be impervious to water. The side of the boat is made of suitable fabric. There is an outer casing formed of two members, one fabric casting 25 being secured between the flange 5 and bar 4 at the bottom and to the oval frame 1 at the top. The other part 26 of the outer casing is held to the bar 7 by nuts 8 and is secured, also, to the oval frame 1. A plate 27, retained in place by bolts 28, grasps the upper edges of the fabric members 25 and 26 and clamps same to the oval frame, thus preventing tearing of the fabric. Between the two fabric members 25 and 26 is an inner tube 30 which can be inflated by a suitable pump, the oval frame 1 being perforated at 31 to permit such inflation.

I claim as my invention:

1. A collapsible boat comprising a bottom, an upper frame, ribs in pivotal connection with one of said members, toothed I-beams in connection with the other of said members, the ends of said ribs opposite said pivotal connections being adapted to ride upon said I-beams, said ribs being slotted to 30 receive the outer flanges of said I-beams, and

a finger upon each rib adapted to engage the under or inner side of the flange of the I-beam engaged by said rib.

2. The combination with a bottom of a frame movable with respect thereto, lugs formed on said frame, ribs pivoted to said lugs and slotted at their free terminals, longitudinal and transverse beams arranged in the bottom of the boat and spanned by the slotted terminals of the ribs aforesaid, and means for interengagement between the ribs and the beams aforesaid.

3. The combination with a bottom of a frame movable with respect thereto, lugs formed on said frame, ribs pivoted to said lugs and slotted at their free terminals, longitudinal and transverse I-beams so arranged that their top webs are reciprocatingly engaged by the slotted terminals of said ribs, and teeth formed in the upper webs of said I-beams for engagement with said ribs for retaining the same in their adjusted positions.

In testimony whereof I hereunto affix my signature in the presence of two witnesses. 55

GEORGE DUBOIS.
